US00D867577S

(12) **United States Design Patent** (10) **Patent No.:** **US D867,577 S**
(45) **Date of Patent:** **** Nov. 19, 2019**

(54) **HEADGEAR ASSEMBLY**

(71) Applicant: **Fisher & Paykel Healthcare Limited**,
Auckland (NZ)

(72) Inventors: **Bruce Michael Walls**, Auckland (NZ);
Rex Gordon Faithfull, Auckland (NZ);
Arvin San Jose Gardiola, Auckland
(NZ); **Wen Dong Huang**, Auckland
(NZ); **Matthew Robert Geoff Slight**,
Auckland (NZ)

(73) Assignee: **Fisher & Paykel Healthcare Limited**,
Auckland (NZ)

(**) Term: **15 Years**

(21) Appl. No.: **29/680,929**

(22) Filed: **Feb. 21, 2019**

Related U.S. Application Data

(60) Continuation of application No. 29/640,467, filed on
Mar. 14, 2018, now Pat. No. Des. 848,607, which is
a division of application No. 29/581,677, filed on Oct.
20, 2016, now Pat. No. Des. 815,728, which is a
division of application No. 29/475,080, filed on Nov.
27, 2013, now Pat. No. Des. 770,036.

(57) **CLAIM**

The ornamental design for a headgear assembly, as shown
and described.

DESCRIPTION

FIG. 1 is a top, front and right side perspective view of a
headgear assembly embodying the new design;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

Broken lines are used to illustrate portions that form no part
of the claimed design.

1 Claim, 7 Drawing Sheets
